UNITED STATES PATENT OFFICE.

JOHN L. FITZGERALD, OF BOSTON, MASSACHUSETTS.

LOW-WATER ALARM FOR STEAM-BOILERS.

1,130,385.

Specification of Letters Patent. Patented Mar. 2, 1915.

Application filed September 10, 1913. Serial No. 789,128.

To all whom it may concern:

Be it known that I, JOHN L. FITZGERALD, citizen of the United States, residing at Boston, in the county of Suffolk and State of Massachusetts, have invented certain new and useful Improvements in Low-Water Alarms for Steam-Boilers, of which the following is a specification.

This invention relates to low water alarms for steam boilers and has as its object to provide an alarm which will be positive in its action and will give both visual and audible warning of low water conditions.

15 Another object of the invention is to provide a low water alarm so constructed that it will serve also as an indicator to show at all times the level of the water in the boiler.

The invention also aims to provide a device of the class mentioned which may be readily applied to practically any type of steam boiler without any material alteration in the construction of the boiler and at little expense.

25 In the accompanying drawings: Figure 1 is a view in elevation of the alarm applied to a boiler. Fig. 2 is a vertical longitudinal sectional view through the device. Fig. 3 is a transverse section on the line 3-3 of Fig. 2. Fig. 4 is a similar view on the line 4-4 of Fig. 2. Fig. 5 is a plan view of the indicator. Fig. 6 is a transverse section on the line 6-6 of Fig. 2.

The alarm embodying the present invention includes a tubular casing 1 which is fitted through the boiler shell indicated by the reference character B and secured in place in any suitable manner, as illustrated in Fig. 1 of the drawings. At one end the 35 casing 1 is interiorly threaded as at 2 and fitted in its said end is one branch of a T-shaped casing section 3. The casing section 3 has a steam inlet branch 4 which preferably projects downwardly from the horizontal branches and interiorly and at the upper end of the passage in the branch 4 the said casing section is of substantially semi-spherical formation as indicated at 5, so as to provide a seat for a spherical valve member which will be presently described. The valve member mentioned above is in the nature of a tube 6 provided at a point between its ends with a spherical enlargement 7 fitting within the seat 5 and having an opening 8 adapted to register with the upper end of the passage in the inlet branch 4 of

the casing section 3 when the tube 6 is rotated, it being observed that the tube is mounted for rotation in the horizontal branches of the casing section 3. That one 60 of the branches which is fitted into the end of the tubular casing 1 is interiorly of a diameter to fit the tube 6 of the valve member and in order that the parts may be assembled the other horizontal branch of the 65 section 3 is interiorly of a diameter to receive the spherical enlargement 7. In order that the tube may have bearing in both of the branches, a bushing 8 is threaded into the last-mentioned branch and co-operates 70 with the spherical enlargement 7 in a manner clearly shown in Fig. 2 of the drawings. A cap 9 is fitted on to the end of the tubular casing 1 opposite the end into which the casing section 3 is fitted, and this cap is provided interiorly and axially with an inwardly flared nipple 10 which communicates with one end of a steam passageway 11 extending from the cap. The passage 11 is provided with a branch 12 to which is connected the stem 13 of a whistle 14 constituting the audible signal of the device. The tube 6 extends axially within the tubular casing 1 and terminates within the cap 9 and this end of the tube has fitted to it a 85 cap 15 having a tapered nipple 16 which fits frictionally within the nipple 10. By this construction this end of the tube 6 is supported for rotation and the tube is placed in communication with the steam passage 11 and the branch 12 so that when the tube 6 has been so rotated as to bring the opening 8 in registration with the intake branch 4 steam will be admitted to the whistle 14 to indicate low water in the boiler. 90

95 For a purpose to be presently explained, the steam pipe 11 is extended beyond the branch 12 as indicated at 17 and has fitted to its end a cap 18. A collar 19 is fitted on to the second-described branch of the casing section 3 and projects beyond the branch and is provided exteriorly with a ball race 20. A two-part ring consisting of sections 21 has its said sections formed with matching ball races 22 and the continuous ball race thus formed co-operates with the race 20 when the sections are assembled about the collar 19, bearing balls being arranged within the races. A cap 24 is threaded to the ring 21 and serves to hold the sections thereof in assembled relation and this cap is provided axially with a short tubular extension 100 105 110

- 25, which, as will be observed from an inspection of Fig. 2, is in axial alinement with the tube 6. A sleeve 26 is provided at one end with a cap portion 27 which is threaded 5 on to the end of the tube 6, which projects into the collar 19 and the said sleeve 26 and fits within the tubular extension 25 of the cap 24 as clearly shown in the said Fig. 2 and in Fig. 6.
10. In order that rotative movement may be imparted to the tube 6 as the water level in the boiler rises and falls, there is provided a float 27 having an arm 28 provided at one end with a head 29 fitted over the tubular 15 extension 25 of the cap 24, and a pin 30 is fitted through registering openings in the head 29, tubular extension 25, and sleeve 26, and serves to connect the parts for rotation in unison, as will be apparent.
20. The indicator device includes a stem 31 which at one end is provided with a square enlargement 32 fitted within the sleeve 26 and provided with an opening 33 through which the pin 30 projects. The other end 25 of the stem 31 extends through the cap 18 at the end of the steam pipe extensions 17 and has fixed upon it a bevel gear 34. A bracket 35 is secured upon the extension 17 and supports the indicator dial 36 in which 30 is rotatably mounted a stem 37 carrying a beveled gear 38 which meshes with the gear 34. An indicator hand or pointer 39 is fixed upon the stem 37 and cooperates with the face of the dial 36 to indicate the water level 35 or the volume of water within the boiler, as may be desired.
- From the foregoing description of the invention it will be understood that when the water level falls the tube 6 will be rotated so 40 as to bring the opening 8 into registration with the upper end of the intake branch 4, thereby admitting steam to the whistle 14, the parts having been, of course, so adjusted that steam will not be admitted until the 45 level has fallen approximately to the danger point. It will also be apparent that as the float 27 rises and falls the stem 31 will be rotated and the indicator hand 39 will move

over the face of the dial 36 to indicate variations in the water level or in the volume 50 of water within the boiler, as may be desired.

Having described my invention, what I claim is:

1. In a low water alarm, a casing having 55 an inlet, a steam conducting pipe rotatably mounted in the casing and having an opening adapted to be brought into communication with the inlet, float actuated means for rotating the pipe, and indicator mechanism 60 including an actuating stem extending within the pipe and connected to said means for rotation therewith.

2. In a low water alarm, a casing having 65 an inlet, a steam conducting pipe rotatably mounted in the casing and having an opening adapted to be brought into communication with the inlet, indicator mechanism including a stem extending within the pipe, a float having an arm, and means connecting the arm with the pipe and stem for rotating the said pipe and stem.

3. In a low water alarm, a casing having 70 an inlet, a steam conducting pipe rotatably mounted in the casing and having an opening adapted to be brought into communication with the inlet, an audible signal in communication with the pipe, a head rotatably fitted upon one end of the casing and having a tubular extension, the pipe having a portion 75 fitting within the extension, indicator mechanism including an actuating stem extending through the pipe and having one end fitted within the said portion of the pipe, a float having an arm provided with a head fitted 80 to the tubular extension of the first-mentioned head, and means extending through the interfitted elements to connect the stem and pipe for rotation with the casing head upon rise and fall of the float.

In testimony whereof I affix my signature in presence of two witnesses.

JOHN L. FITZGERALD. [L.S.]
